DOOR LOCK WITH BUTTON LOCKING MEANS

Ernest L. Schlage, Burlingame, and Armin H. Green, San Mateo, Calif., assignors to Schlage Lock Company, a corporation

Filed June 18, 1959, Ser. No. 821,203

7 Claims. (Cl. 70—216)

This invention relates to door locks and particularly to locking means carried by the inside knob for locking the outside knob.

In conventional locksets the inside spindle usually is provided with a push button or turn button which is actuated to lock the outside knob spindle or key spindle against rotation. In the case of the push button type, the outer spindle is locked against rotation when the button is in its inner or depressed position and is unlocked when the push button is in its outer or projected position. The operation of the inside spindle is not usually affected by the position of the push button thus providing the conventional "panic proof" feature.

The turn button type of lockset usually requires that the button be turned about a quarter turn to retain the button in locking position. In such a case the outside spindle usually remains locked until the button is manually restored to its unlocked position. This is unlike the normal push button type of lockset in which rotation of the inside spindle or closing of the door restores the button to unlocked or projected position. However, in some instances a nonrestoring push button is employed.

The main object of the present invention is the provision of a push button type of locking means which is adapted to be moved to a locked position in which it is not automatically returned to projected or unlocked condition by closing the door and in which locked position it prevents unlocking the door in the usual manner.

In this connection it is advantageous in some instances to provide a push button type of lockset in which the push button may be moved to a special locked position in which the lockset may not be unlocked by means of the pass key which is ordinarily employed under normal circumstances.

An example of such a use is in an hotel where the outside knob of the guest's room is fixed relative to the door and rotation of the key plug by means of a key is required to retract the latchbolt. In such a case it is desirable to be able to block the keyway against entrance of a pass key by depressing the push button on the inside knob and at the same time to automatically unblock the keyway when the door is closed as the guest leaves. Examples of key shut-out devices actuated in this manner are shown in U.S. Patent No. 2,738,666, issued March 20, 1956, No. 2,008,405, issued July 16, 1935; and No. 1,944,469 issued January 23, 1934.

In such a hotel lockset it is further desirable to provide a special locking function wherein the key shut-out device may be actuated and remain actuated after the door is closed. An example of such use would be on a hotel lockset for a room in which especially valuable articles such as salesmen's samples are stored. In such a case the guest would be provided with a special or emergency key of the type shown in the above noted patents in order to gain entrance to his room. However, the maid or any one else having an ordinary change key or master key would be excluded.

2

The same type of shut-out feature may also be employed by the management to shut out the guest's own change key when desired.

The above noted main object of the present invention is achieved by providing relatively great resistance to turning the button to a special locked position to which it may not be turned inadvertently or otherwise during normal use.

Another object of the invention is the provision of means for centering a universal button, that is, a button which may be employed both as a push button and a turn button.

In this connection it will be noted that it is preferable to retain such a universal button in a predetermined vertical or horizontal position so as to constitute a visual indication of the condition of the lockset. By the present invention means is provided for imposing a resistance to rotation of the button from the predetermined position in which it acts as a push button so that said button visually indicates the condition of the lockset at all times.

Other objects and advantages will be apparent from the specification and the drawings.

Fig. 1 is an exploded perspective of the inner spindle 25 of a lockset and its associated mechanism;

Fig. 2 is an elevation of the face of the push button;

Fig. 3 is a fragmentary side elevation of the inner spindle showing the push button in projected or unlocked position with the spanner key in actuating position;

30 Fig. 4 is a view similar to Fig. 3 with the push button turned by means of the spanner key to an intermediate position;

Fig. 5 is a view similar to Fig. 3 showing the push button turned to its special locked position;

35 Fig. 6 is a side elevation of a modified cam plate incorporating a button centering cam;

Fig. 7 is a fragmentary side elevation of the inner spindle incorporating the modified cam plate of Fig. 6;

40 Fig. 8 is a longitudinal cross section through an inner spindle showing a modified form of the invention employing a torsion spring;

Fig. 9 is a side elevation of the spindle of Fig. 8 showing the push button in its special locked position;

Fig. 10 is a side elevation of the spindle of Fig. 8 45 showing the button being turned towards its special locked position.

In detail, and with reference to Fig. 1, the invention is adapted to be applied to an inner spindle generally designated 1 and to which the inner knob (not shown) is 50 adapted to be releasably secured. The cylindrical shank portion of the knob slides over the spindle 1 and is provided with a rectangular opening into which a knob catch 2 is spring pressed by means of a flat spring, a portion of which is shown at 3 in Fig. 1. The knob catch 55 2 extends inwardly of the spindle to form a pair of ears 4 which are provided with lugs 5 reciprocably disposed in slots 6 formed in the sidewall of spindle 1. By this structure catch 2 and its associated ears 4 may be depressed to permit the knob to be secured to spindle 1 60 and spring 3 acts to project the catch 2 into the complementarily formed opening in the knob.

Spindle 1 is formed at its free end with a generally L-shaped slot 10 which includes a circumferentially extending portion 11 and an axially extending portion 12 65 opening outwardly of the end of the spindle 1. Slot 10 is adapted to receive therein a lug 13 formed on the base plate 14 of the push button 15 (Fig. 1). Said base plate and button are rotatably received on one end of a locking bar 18 which is provided with a catch 19 adapted to 70 engage the retractor (not shown) in the conventional manner when the push button is depressed so that retrac-

tion of the retractor releases the catch 19 to permit the bar 18 to be returned to its projected position.

In the case of a key operated outer spindle the return of bar 18 to its projected position is effected by means of a compression spring 21 which urges a cup member 22, slidably mounted in the outer key spindle (not shown), against the inner end 23 of locking bar 18. In other words the spring 19 urges the push button 15 outwardly of the outer end of spindle 1 at all times.

The above described push button locking structure is conventional and no claim is made thereto except in combination with the other devices now to be described.

By the present invention a cam plate 25 is slidably disposed in spindle 1 in face to face engagement with the base plate 14 of button 15 and is urged into such engagement at all times by a compression spring 26 surrounding bar 18. The opposite end of spring 26 may be conveniently positioned against the ears 4 of knob catch 2 without interfering with the proper functioning of the latter.

At this point it may be noted from Fig. 3 that the push button 15 may be depressed from the projected position shown without rotation of said button so that catch 19 on locking bar 18 is hooked to the retractor to lock the outer spindle or to shut out the change key depending on the type of lock employed. In such a case the lug 13 of push button 15 merely reciprocates along the axially extending portion 12 of the L-shaped slot 10 between its depressed and projected positions.

In the event it is desired to shut out the change key from the outer knob even after the door is closed, it is necessary to hold the push button 15 in its depressed position against projection by spring 21. This is done by depressing the push button 15 inwardly and then rotating the same so that lug 13 is received within a notch 28 at the closed end of the circumferentially extending portion 11 of the L-shaped slot 10 (Fig. 3). However, in order to prevent inadvertent rotation of button 15 to the key shut out position a predetermined relatively great resistance must be offered to such rotation. Such resistance is provided by the shape of cam plate 25.

As best seen in Fig. 1, cam plate 25 is provided with a central aperture 29 sufficiently large to permit said plate 25 to engage base plate 14 of push button 15. Cam plate 25 is also formed with peripherally extending flanges 30, 31 to permit the plate to slide within spindle 1. An integral lug 32 is also formed on the cam plate to be received within the axially extending slot 33 in spindle 1 so as to prevent any relative rotation between the plate and the spindle.

Struck from the plate 25 and bent in the opposite direction from flanges 30, 31 is a flange 35 which is provided with a slantingly disposed camming edge 36 for a purpose now to be described. Referring to Figs. 3-5 it is seen that the juncture of the L-shaped slot 10 between portions 11, 12 is enlarged to form a slantingly disposed edge 38 which has the effect of urging the lug 13 inwardly of the spindle as the push button 15 is rotated in the direction indicated in Fig. 4.

As best seen in Fig. 4, as the lug 13 approaches the notch 28, it will be apparent that said lug is required to force the flange 35 of camming plate 25 away against the resistance of spring 26 in order to enter notch 28. Because of the presence of the opposed edges 36 and 38 and further because of the fact that they are slantingly disposed relative to the direction of movement of lug 13 sufficient resistance to rotation of button 15 is provided so that lug 13 cannot be made to enter notch 28 without special means for effecting a relatively high torque.

Such special means may be a spanner key 40 (Fig. 1) provided with a pair of projections 41 adapted to be received within complementarily formed holes 42 in the outer face of button 15 (Fig. 2). When key 40 is thus

employed sufficient torque may be developed by the user to overcome the resistance offered by cam plate 25.

From the above described structure it will be apparent that the lockset may be operated under normal conditions in the same manner as any push button lock with a key shut-out attachment so that the shut-out will be rendered inoperative when the guest leaves the room and closes the door behind him.

However, when it is desired to leave the room and at the same time retain the key shut-out in operative position the spanner key 40 may be employed to depress and rotate the button 15 to the special locked position of Fig. 5. In such a case even the guest employing the change key or the maid employing a master key cannot open the door. It is then necessary to employ a special key which is especially designed to enter the keyway despite the presence of the key shut-out.

It is understood that the present invention may be employed in conjunction with any conventional shut-out means and no claim is made herein to such means per se.

In order that the button 15 may act as a visual indication of the condition of the lock it is preferable that the button 15, while in its normal depressed position, be disposed with the holes 42 therein arranged horizontally or vertically and not in some intermediate position. Of course when the button is in its unlocked or projected position lug 13 is held in slot portion 12 against rotation.

For the purpose of preventing button 15 from shifting while in its depressed position from a predetermined position relative to the orientation of holes 42 the cam plate may be modified as shown in Fig. 6.

In this case the cam plate 45 of Fig. 6 is the same in all respects as the cam plate 25 except that in addition to have a camming flange 46 corresponding to flange 35 of cam plate 25 it is also formed with a centering cam 47 providing a slanting edge 48 along which lug 13 of button 15 must slide to rotate said button from its normal depressed position. Thus, as best seen in Fig. 7, when the button 15 is in its normal depressed position the slanting edge 48 of centering cam 47 prevents rotation of said button. However, when it is desired to rotate the button 15 to the special locked position corresponding to that shown in Fig. 5 it is a simple matter to overcome the resistance offered by cam 47 and spring 26 by means of spanner key 40.

Another method of offering resistance to turning button 15 is shown in Figs. 8-10 wherein the cam plate is omitted and reliance is made on only a torsion spring 50 which is secured at one end to the knob catch 2 and its other end to the base plate 14 of push button 15. By installing spring 50 in a wound up condition it serves to rotate button 15 in a direction such that it tends to stay in the axially extending portion 12 of slot 10. In such a case it is seen that both the slanting edge 38 (Fig. 10) and the torsion of spring 26 cooperate to oppose movement of the button 15 toward the special locked position of Fig. 9.

Although the torsion spring employed in the structure shown in Figs. 8-10 is suitable for the desired purpose under many conditions it has the disadvantage of automatically returning the button to the normal position from the shut-out position if the knob is subjected to an abnormal shock. In the preferred structure of Figs. 1-7 the cam plate 25 directly engages the lug 13 and positively prevents return of the push button to its normal position except when a strong torque may be exerted thereon as by spanner key 40.

The invention herein disclosed is not to be taken as restricted to any particular kind of push button since it may be employed in connection with various functions. Nor should the detailed description of the preferred forms of the invention be taken as restrictive thereof since minor variations in design may be resorted to without departing from the spirit of the invention as defined in the following claims.

We claim:

1. In a lockset having a reciprocably mounted locking element movable longitudinally of the inner spindle of said lockset between an outer projected position corresponding to an unlocked condition of said lockset to an inner depressed position corresponding to a locked condition of said lockset, a compression spring for urging said element to said outer position at all times, a button carried by said element at the outer end of said inner spindle, said button being rotatable relative to said spindle when said element is in said depressed position from a normal position to an angularly offset position, interengaging elements on said button and said spindle respectively for holding said button in said offset position, and means for imposing a relatively strong resistance to rotation of said button toward said offset position in addition to the resistance offered by said spring, said last mentioned means comprising a plate fixed against rotation relative to said spindle and provided with a cam portion adapted to be engaged by said button as the latter is rotated to said offset position, said cam portion being formed to urge said button outwardly of said spindle during said rotation of said button to said offset position.

2. In a lockset having a reciprocably mounted locking element movable longitudinally of the inner spindle of said lockset between an outer projected position corresponding to an unlocked condition of said lockset to an inner depressed position corresponding to a locked condition of said lockset, a compression spring for urging said element to said outer position at all times, a button carried by said element at the outer end of said inner spindle, said button being rotatable relative to said spindle when said element is in said depressed position from a normal position to an angularly offset position, interengaging elements on said button and said spindle respectively for holding said button in said offset position, and means for imposing a relatively strong resistance to rotation of said button toward said offset position in addition to the resistance offered by said spring, said last mentioned means comprising a plate fixed against rotation relative to said spindle and provided with a cam portion adapted to be engaged by said button as the latter is rotated to said offset position, said cam portion being formed to urge said button outwardly of said spindle during said rotation of said button to said offset position, and a centering element on said plate for resisting angular movement of said button relative to said spindle when said button is in said normal position.

3. In a lock spindle adapted to receive the inner knob of a lockset thereon, a turn button mounted in said spindle and angularly movable relative thereto from a normal position to a locked position, the sidewalls of said spindle being formed with a circumferentially extending slot, and said button being provided with a radially outwardly projecting lug received in said slot, a plate received in said spindle and held against rotation relative thereto, said plate being formed with a camming portion engageable by said lug upon movement of said button to said locked position for imposing a predetermined relatively great resistance to said movement.

4. In a lock spindle adapted to receive the inner knob of a lockset thereon, a turn button mounted in said spindle and angularly movable relative thereto from a normal position to a locked position, the sidewalls of said spindle being formed with a circumferentially extending slot, and said button being provided with a radially outwardly projecting lug received in said slot, a

plate received in said spindle and held against rotation relative thereto, said plate being formed with a camming portion engageable by said lug upon movement of said button to said locked position for imposing a predetermined relatively great resistance to said movement, said plate being positioned relative to said slot whereby said lug is engaged on opposite sides by said portion and an edge of said slot respectively during said movement for so imposing said resistance.

5. In a lock spindle adapted to receive the inner knob of a lockset thereon, a turn button mounted in said spindle and angularly movable relative thereto from a normal position to a locked position, the sidewalls of said spindle being formed with a circumferentially extending slot, and said button being provided with a radially outwardly projecting lug received in said slot, a plate received in said spindle and held against rotation relative thereto, said plate being formed with a camming portion engageable by said lug upon movement of said button to said locked position for imposing a predetermined relatively great resistance to said movement, and spring means engaging said plate for urging the latter outwardly of said spindle at all times.

6. In a lock spindle adapted to receive the inner knob of a lockset thereon, a turn button mounted in said spindle and movable longitudinally thereof between an outer projected position and an inner depressed position, said button being rotatable relative to said spindle from a normal position to a locked position, the sidewalls of said spindle being formed with a circumferentially extending slot, and said button being provided with a radially outwardly projecting lug received in said slot and movable therewith during said rotation between the axially spaced inner and outer edges of said slot, the outer edge of said slot being slanted to urge said lug inwardly of said spindle upon said rotation of said button from said normal position to said locked position, means engaging said lug on the side of the latter opposite the side engaged by said slanted edge during said rotation, said last mentioned means including a camming edge urging said lug toward said slanted edge, and spring means urging said camming edge toward said slanted edge for providing a substantial resistance to said rotation.

7. In a lockset having a reciprocably mounted locking element movable longitudinally of the inner spindle of said lockset between an outer projected position corresponding to an unlocked condition of said lockset to an inner depressed position corresponding to a locked condition of said lockset, a compression spring for urging said element to said outer position at all times, a button carried by said element at the outer end of said inner spindle, said button being rotatable relative to said spindle when said element is in said depressed position from a normal position to an angularly offset position, interengaging elements on said button and said spindle respectively for holding said button in said offset position, and means for resisting rotation of said button from said depressed position, said last mentioned means comprising a plate fixed against rotation relative to said spindle and provided with a projection cooperating with said button for so resisting said rotation.
